UNITED STATES PATENT OFFICE.

CHARLES CHESTER EATON, OF BROCKTON, MASSACHUSETTS, ASSIGNEE TO C. A. EATON COMPANY, OF BROCKTON, MASSACHUSETTS, A CORPORATION OF MASSACHUSETTS.

PROCESS OF MAKING SHOES.

1,103,913.

Specification of Letters Patent. Patented July 14, 1914.

Application filed June 11, 1913. Serial No. 772,984.

To all whom it may concern:

Be it known that I, CHARLES CHESTER EATON, a citizen of the United States, and resident of Brockton, county of Plymouth, State of Massachusetts, have invented an Improvement in Processes of Making Shoes, of which the following description, in connection with the accompanying drawings, is a specification, like letters on the drawings representing like parts.

This invention relates to footwear of the spring heel type, and more particularly to an improved process of making such footwear. The manufacture of spring heel shoes has heretofore been limited to the smaller sizes of infants' and children's shoes, and has not been considered as suitable for the manufacture of full size footwear for men and women. Children's and infants' spring heel shoes have usually been made with a single sole, of the "turn" shoe type or of the "stitched-down" type of shoe, and the heel end of the outer sole has frequently been split, cut, or recessed so that it could be properly "sprung" around a heel lift, and the heel portion of the sole so sprung was nailed to the shoe in the usual manner.

My invention contemplates the production of a spring heel type of shoe, employing both an insole and an outer sole. I also prefer to make such a shoe with a cushion heel, and protect the cushion so that it will be free from wear and will nevertheless act as the heel lift to give extra height to the heel around which the outer sole is to be sprung to constitute the heel of the shoe. As herein shown in a preferred form, I have illustrated the process of making my improved shoe as an athletic type of shoe, although my process is equally applicable to shoes of any style or type employing a spring heel. In carrying out my novel process I first prepare an inner sole with a welt channel, extending said channel entirely around the heel portion of the inner sole, as well as around the forepart. I then assemble the upper and inner sole on a last in the usual manner and stitch thereto a welt by the usual welt inseam stitching machine, stitching the welt entirely around the heel, so that the assembled shoe thus prepared is supplied with a welt stitched entirely around the marginal portion of the upper, as well as to the insole. Preferably I start and end the welt on the arch side of the shoe

at the heel breast, *i. e.* at the left on a right, and at the right on a left, shoe. I then prepare the outer sole by first molding the same to substantially the shape at the heel breast which it is to occupy in the completed shoe. During this molding operation I also provide the outer surface of the outsole with corrugations or the like anti-slipping devices, particularly when the sole is to be applied to an athletic shoe. This molding of the outer sole also condenses and compacts the leather thereof, adding considerably to the wearing qualities and forming the corrugations in the outer surface still further increases this condensing or compacting of the fibers of the leather. I prefer to so mold the outer sole that the heel breast will be at an angle slanting inwardly and forwardly to the arch of the shoe, in order to afford an arch supporting or orthopedic effect under the arch. I further so mold the outer sole as to form the heel breast of greater depth at the forwardly extended portion of the spring heel to add to the thickness of the support for the arch, thus securing a further orthopedic feature, all being within the purview of my patent. To the sole thus molded I apply at the heel portion a cushion heel lift adapted to exactly register with the extent to which said heel has been molded, both with regard to the angle of the heel breast and the increasing depth at one side relatively with the depth at the other side, so that said heel lift will render the inner surface of the outer sole substantially level throughout its entire extent when applied to the welted shoe preparatory to being stitched thereto. I then stitch the outsole to the welt with a usual outsole stitching machine, the stitching passing entirely around the heel and through the cushion lift.

In the drawings, illustrating an athletic orthopedic shoe made by my improved process, Figure 1 is a side view of such a shoe; Fig. 2 is a view of the outer sole after it is molded, and with the cushion heel lift applied thereto; Fig. 3 is a view of the bottom of the sole after it is molded and corrugated; and Fig. 4 is a view in cross section on the line 4—4 of Fig. 3.

The shoe upper is indicated at 1, a usual type of Oxford or low shoe being shown, the upper 1 being united to a channel insole 2 and a welt 3 by inseam stitching 4, as illustrated in Fig. 4. It will be understood that

the welt groove or channel in the insole 2 is cut entirely around the heel in order to allow for the stitching of the welt 3 entirely around the heel also, a stitched heel seat being, thus provided in contra-distinction to the usual nailed heel seat. A suitable filling 5 may be applied to both forepart and heel part of the shoe, and the outsole 6, together with the cushion heel lift 7, which 10 have been molded and cemented together as above explained, and constituting a combined heel and sole, are then applied to the shoe and the outsole stitching 8 is put in through the welt 3, the sole 6 and around 15 the heel portion through the cushion lift 7, also uniting the sole, heel lift and welt firmly together.

The shoe made by my improved process is of extreme flexibility, as well as of the 20 cushion heel type, said cushion being secured without nails, and, in fact, the entire shoe is completed by my process without a nail or tack being left in it. The cushion heel lift 7 may be of any suitable thickness 25 desired, and while preferably of rubber or rubber-composition, may be of other yielding and resilient material. The outsole stitching 8 which secures the cushion heel 7 to the shoe permits the cushion to yield and 30 be flexed without any restraint and without affecting the holding of the stitches. In the shoe herein illustrated it will be seen that the heel breast 9 is preferably formed at an angle having the forwardly extended and 35 thicker portion at the arch side 10 of the shoe thus causing the insole of a shoe to fit up snugly under the arch of the foot, and provide an arch supporting, as well as orthopedic, construction. Preferably I make the 40 shoe of the type herein shown without a shank stiffener or the like rigid means, although such a stiffener could be employed if desired. My improved process, therefore, enables a cushion heel shoe to be made of 45 the spring heel type, suitable for adult wear, and furthermore provides an extremely flexible shoe and without a nail or tack in its entire construction. Furthermore, by molding the outer sole, as explained, I secure 50 the advantages of the full limit of thickness and wearing capability of the outer sole, both at the heel breast 9 and throughout the entire extent of the heel. This is of great 55 importance, as heretofore it has been customary to cut the heel portion of a spring heel shoe at the heel breast and to decrease the wearing thickness of the sole at this point. By employing a welt construction around the heel, the shoe can be readily 60 paired and the cushion heel lift 7 can be replaced, should it wear out before the outer sole. By having the cushion lift, however, thus protected between the outsole and the

heel of the shoe, its wearing capacity is greatly lengthened and the full capacity of 65 its yield or resilience is left unimpaired.

Having described my invention, what I claim as new and desire to secure by Letters Patent is:

1. The process of making an orthopedic, 70 spring heel shoe, which comprises molding the outsole with the heel portion thereof offset below the level of the adjacent end of the shank portion to form a recess for a heel lift, and with the portion of the sole 75 connecting said shank portion with said heel portion extending from the outside of the shank forwardly across the sole to the inside of the shank to form an inclined heel breast of gradually increasing depth from 80 said outer side of the shank to said inner side thereof, securing a heel lift in said recess of such dimensions that the upper surface of said lift is substantially flush with the upper surface of said shank along their 85 contacting edges, and finally securing the sole and heel lift to a shoe.

2. The improved process of making a shoe having a leather outsole, comprising molding the tread surface of the outsole in substantially its final form, simultaneously condensing portions of the outsole by a plurality of intersecting indentations, thereby forming spaced flat tread surfaces between 90 said indentations to constitute antislipping 95 devices, then applying the sole so prepared to the bottom of a shoe having an upper, insole and welt extending entirely around the shoe bottom, and stitching the marginal portion of the sole and welt together. 100

3. The improved process of making a shoe having a leather outsole, comprising molding the tread surface of the outsole in substantially its final form with the heel portion of the sole offset to constitute the tread 105 face of the heel, simultaneously condensing both forepart and heel portions of the outsole by a plurality of intersecting indentations thereby forming spaced flat tread surfaces between 110 said indentations to constitute antislipping devices, then applying the sole so prepared to the bottom of a shoe having an upper, insole and welt extending entirely around the shoe bottom, interposing 115 an orthopedic cushion heel lift between the heel and said offset portion of the outsole, and stitching the marginal portion of the sole, cushion heel lift, and welt together.

In testimony whereof, I have signed my name to this specification, in the presence of 120 two subscribing witnesses.

C. CHESTER EATON.
